UNITED STATES PATENT OFFICE.

CHRISTOPH. BREUSCHER, OF PLANO, ASSIGNOR TO THE PLANO MANUFACTURING COMPANY, OF CHICAGO, ILLINOIS.

GRAIN-BINDER.

SPECIFICATION forming part of Letters Patent No. 433,644, dated August 5, 1890.

Application filed October 17, 1889. Serial No. 327,298. (No model.)

To all whom it may concern:

Be it known that I, CHRISTOPH. BREUSCHER, a citizen of the United States, residing at Plano, in the county of Kendall and State of Illinois, have invented certain new and useful Improvements in Grain-Binders, which are fully set forth in the following specification, reference being had to the accompanying drawings, in which—

10 Figure 1 represents a side elevation of a knotter-frame for a binder, partly in section, containing my improvements; Fig. 2, an end elevation of the same; Fig. 3, a detail of the pawl and notched wheel of the cord-holder, taken on an enlarged scale; and Fig. 4, a detail plan of a section from the lower part of the frame upon the same enlarged scale.

15 My invention relates to automatic grain-binders for harvesting-machines; and it consists in certain improvements in the devices for operating the notched disk or wheel, which constitutes a part of the cord-holder.

I will describe in detail so much of a binding-machine as is necessary to an understanding of my invention, and will then point out definitely in claims the special improvements which I believe to be new and wish to secure by Letters Patent.

20 As the invention relates simply to a special part of the binder, I have not shown and shall not describe the full machine, and only those parts of the binder are illustrated by the drawings which are necessary to an understanding of the construction and operation of my present improvement.

25 In the drawings, A represents the cam and gear shaft of a grain-binder, and B the knotter-frame, which is mounted loosely on said shaft in the usual way. The cord-holding disk C is mounted in the lower part of the frame in the usual way, being provided with the usual notches c and also with a ratchet wheel or hub c', this feature being also an ordinary device. The usual keeper D is of course provided to receive one edge of the disk, so that the binding-cord will be clamped therein.

30 At the upper end of the knotter-frame B a stud or lug b projects out from the side opposite to that on which the cord-holder is located, as seen in Fig. 2 of the drawings. A

yoke E is pivoted at one end to the outer end of this lug and extends to the other side of the knotter-frame in a direction perpendicular to the shaft A, which it is arranged to embrace. This yoke is considerably larger than the shaft, so that considerable free vertical vibration of the former is permitted upon its pivot. At the end of the yoke opposite to the pivot and on the opposite side of the knotter-frame a pawl F is connected thereto at its upper end by a hinge or pivot joint. This pawl is nearly straight and depends from the end of the yoke about straight downward, the yoke being of such length that the lower end of the pawl is brought into the same plane as the ratchet-wheel on the notched disk, as seen in Figs. 1 and 3 of the drawings. At the lower end of the pawl is a hook f, which is adapted to engage with the teeth of the ratchet, and a spring f' is fastened to the back thereof, by means of which the pawl is held up toward the ratchet, so as to engage with its teeth. This is effected by making an angular bend b in the lower bar of the knotter-frame directly opposite the teeth of the ratchet, so that the pawl will stand between this shoulder or bend and the ratchet, and the spring upon the back of the pawl will find a bearing against this shoulder, thereby forcing the lower end of the pawl forward into proper position to engage with the ratchet, as seen in Fig. 1 of the drawings. Now it is evident that if the yoke is vibrated vertically upon its pivot it will give a reciprocating movement to the pawl in the same direction, and the latter being made of suitable length the upward movement will cause it to engage with the ratchet, and so turn the notched disk, as required, while the downward movement will thrust the pawl downward past the ratchet-teeth in position for another engagement therewith, the back spring yielding to permit this movement, and so the desired intermittent rotation of the notched disk will be effected. This desired vibration of the yoke is obtained by a suitable cam G on the shaft within the yoke. As shown in the drawings, this device consists of a lug g upon a collar g', which is fastened on the shaft. This lug stands just outside of the plane of the upper and lower arms of the yoke and

upon its inside carries a small anti-friction roller g^2 , mounted on a pivot-stud on the inside of the lug and standing in the plane of the upper and lower portions of the yoke. 5 As the shaft is rotated it is evident, therefore, that the roller will be brought alternately in contact with these portions of the yoke, and that when it comes in contact with the upper arm it will raise the yoke on its 10 pivot, and then will depress the same when it strikes its lower arm. The vibration of the yoke necessary to a proper working of the pawl will thus be produced, it being of course understood that the cam must be arranged on the shaft at such a point that this 15 movement of the yoke will be at the proper time to effect the movement of the cord-holding disk at the instant required. It is evident that this yoke operates as a lever for reciprocating the pawl, and so the construction and arrangement of this device may be modified, so long as it is adapted to operate as a lever vibrated by the rotation of the shaft. It is also evident that the construction of the 20 cam on the shaft may be greatly varied, and in fact some other device may be substituted for a cam, provided always that it is adapted to give the proper vibration to the lever by the rotation of the shaft. It will be seen that 25 30 with these devices I obtain a direct action of the pawl in nearly straight lines and with a very few pieces, so that the device is very simple and cheap and at the same time is absolutely certain in its operation.

Having thus described my invention, what I claim as new, and desire to secure by Letters Patent, is—

1. In a grain-binder, the cord-holder disk provided with a ratchet, in combination with a straight pawl, a lever pivoted to the knotter-frame on one side of the latter and on the opposite side connected to the upper end of the pawl and arranged to embrace and entirely inclose the cam-shaft, and a cam mounted on the cam and gear shaft and arranged to vibrate said lever positively, substantially as and for the purposes specified. 40

2. The knotter-frame B, provided with the angular bend b in its lower bar, the ratchet c' on the cord-holder disk, the pawl F, and the spring f', arranged to bear upon the shoulder formed by the bend b in the frame, substantially as and for the purposes specified. 50

3. The cam and gear shaft A, in combination with the knotter-frame B, provided with a lug b, the yoke E, pivoted at one end to said lug and extended across and embracing and entirely inclosing said shaft, the collar g', secured to said shaft and provided with the lug g, the roller g², mounted on a stud on the inside of said lug, the spring-pawl F, pivoted to the free end of the yoke, and the ratchet on the notched disk C, substantially as and for the purpose specified. 55 60
